ATTY'S

UNITED STATES PATENT OFFICE.

OLIVER H. SHROYER, OF ST. LOUIS, MISSOURI.

INTERNAL-COMBUSTION ENGINE.

No. 874,122.

Specification of Letters Patent.

Patented Dec. 17, 1907.

Application filed March 12, 1907. Serial No. 362,053.

To all whom it may concern:

Be it known that I, OLIVER H. SHROYER, a citizen of the United States, and resident of St. Louis, Missouri, have invented certain new and useful Improvements in Internal-Combustion Engines, of which the following is a specification containing a full, clear, and exact description, reference being had to the accompanying drawings, forming a part hereof.

10 My invention relates to an internal combustion engine of the two cycle type, using gas or carbureted air as fuel, and the object of my invention is to provide a simple, inexpensive construction wherein a compression chamber is provided in the lower end of the engine cylinder, and a portion of the piston rod is made in tubular form in order to deliver the explosive mixture from the compression chamber to the interior of the cylinder above the piston.

15 A further object of my invention is to simplify and lessen the amount of packing ordinarily used in the joints of the crank chamber casing, and in the journal bearings in which the engine shaft operates.

20 To the above purposes, my invention consists in certain novel features of construction and arrangement of parts, which will be hereinafter more fully set forth, pointed out in the claims, and illustrated in the accompanying drawings, in which:

25 Figure 1 is a vertical section taken through the center of an internal combustion engine of my improved construction; Fig. 2 is a horizontal section taken on the line 2—2 of Fig. 1; Fig. 3 is a horizontal section taken on the line 3—3 of Fig. 1; Fig. 4 is a vertical section taken approximately on the line 4—4 of Fig. 2, and showing the exhaust ports leading from the cylinder.

30 Referring by numerals to the accompanying drawings:—1 designates the upper portion of the crank chamber casing which is supported in any suitable manner on a rigid frame 2, and detachably secured to the lower end of said upper portion 1 is the lower portion 3 of the crank chamber casing, and journaled in the casing so formed is the usual crank shaft 4. Formed integral with the upper portion 1 of the casing is a water jacketed cylinder 5, in the upper end of which is located the usual spark plug 6. Rigidly fixed to the lower end of the cylinder 5 is a removable head plate 7, and formed integral therewith and extending upwardly

35 into the lower portion of the cylinder 5 is a cylindrical bearing 8, through the lower portion of which is formed a horizontally arranged port 9. Formed through the lower portion of the cylinder 5, directly opposite this port 9, is a gas or carbureted air inlet port 10, and fixed to the cylinder and leading into said port 10 is a mixing valve housing 11, in which operates a spring pressed inlet valve 12. This valve 12 is arranged to be unseated by the suction following the upward movement of the piston in the cylinder 5, and leading into the valve housing 11 is a hydrocarbon tube 13.

40 Arranged for reciprocation through the tubular bearing 8 is a piston rod 14, the upper portion of which is provided with a concentric bore or passageway 15, the lower end of which is extended laterally to form a port 16 which is adapted to register with the port 7; and fixed on the upper end of said rod is a piston 17, which operates in the cylinder 5, and the top surface of which piston is recessed, as designated by 18.

45 Formed through the flange surrounding the recess in the top of the piston is an outlet port 19, which is covered by a deflector plate 20, the ends of which are fixed to the flange on the top of the piston.

50 Formed through the side of the cylinder 5 is a series of exhaust ports 21, with which the port 19 is adapted to register when the piston is at the lower end of its travel; and leading from the exhaust ports 21 is an exhaust pipe 22. Connecting the lower end of the piston rod 14 and the crank of the shaft 4 is a connecting rod 23. Formed integral with the top of the upper portion 1 of the crank casing is a housing 24, which incloses an auxiliary compression chamber 25, and leading from this chamber into the lower end of the cylinder 5 is a port 26, normally closed by a valve 27 carried upon the end of the valve stem 28 which is operated from the exterior of the housing 24.

55 During the operation of the engine the valve 12 is drawn open by the suction resulting from the upward movement of the piston 17 in the cylinder, and during the time said valve is open, hydrocarbon enters through the tube 13, and air is at the same time drawn through the opening in the lower end of the valve chamber 11, thus entering the mixing valve housing together, and passing from thence through the port 10 into the

100

105

110

lower portion of the cylinder 5, beneath the piston 17. The piston on the next downward stroke compresses the charge thus drawn into the lower portion of the cylinder 5, and when said piston and piston rod have reached their lower limit of movement, the port 16 coincides with the port 9, and the explosive mixture under compression passes through the coinciding ports through the 10 port or passageway 15 to the interior of the cylinder above the piston, and said charge being under great compression, naturally passes vertically through the center of the upper portion of the cylinder until it strikes 15 the top thereof, and is thereby deflected downwardly along the interior surface of the cylinder, thus driving the burnt gases resulting from the previous combustion in the cylinder out through the registering ports 19 20 and 21 to the exhaust pipe 22. The piston on its next upward stroke compresses the charge of gas or carbureted air in the upper end of the cylinder, and at the same time draws hydrocarbon and air in through the 25 mixing valve housing, as hereinbefore described; and when said piston reaches its upward limit of movement, the charge compressed within the cylinder above the piston is ignited in the usual manner by the spark 30 plug 6, and said piston is forced downward; and the energy developed by the explosion is transmitted to the crank shaft 4 by means of the piston rod 14 and connecting rod 23 in the usual manner.

35 The deflector plate 20 tends to prevent the discharge of the explosive mixture from the upper end of the cylinder immediately after the burnt gases have discharged through the ports 19 and 21; and, whenever desired, said 40 ports 19 and 21 may be so located as to register slightly in advance of the corresponding action of the ports 9 and 16.

The formation of a passageway through a portion of the piston rod provides simple 45 means for delivering the explosive charge from the compression chamber to the interior of the cylinder above the piston, and all exterior conveying tubes, valves, and ports are thus done away with; and, whenever desired, a larger compression chamber may 50 be provided by merely opening the valve 26, thus bringing the auxiliary compression chamber 25 into communication with the compression chamber below the piston.

55 By providing the head plate 7 in the lower end of the cylinder, and forming the tubular bearing 8 integral therewith, all packing between the crank shaft and crank shaft housing may be dispensed with, as the compression 60 of the explosive charge is accomplished in the lower end of the engine cylinder instead of in the crank chamber casing.

An internal combustion engine of my improved construction comprises a minimum 65 number of parts, is easily assembled, is very

compact, and develops a maximum amount of power with minimum size and weight.

I claim:—

1. An internal combustion engine, comprising a cylinder, a head plate closing the lower end thereof, a tubular piston rod operating through said head plate, a piston within the cylinder on the piston rod, means whereby an explosive charge is delivered to the combustion chamber in the cylinder 75 through the tubular piston rod, and said cylinder being provided with an exhaust port.

2. An internal combustion engine, comprising a cylinder, the lower end of which is closed to form a compression chamber, a piston rod operating through the lower end of the cylinder, there being an inlet port formed through the piston rod, a piston fixed on the piston rod and operating in the cylinder, an inlet valve for controlling the inlet of gas to the compression chamber of the cylinder, and there being a port formed through the bearing for the piston rod at the lower end of the cylinder and leading from the compression chamber with which the port in the piston rod registers when the piston is at the end of its compression stroke.

3. An internal combustion engine, comprising a cylinder, the lower end of which is closed to form a compression chamber, a piston rod operating through the lower end of the cylinder, a piston operating through said cylinder on the piston rod, means whereby an explosive charge is drawn into the compression chamber on the lower end of the cylinder, and means whereby the explosive charge is delivered through the piston rod to the end of the cylinder opposite the compression chamber.

4. An internal combustion engine, comprising a cylinder, the lower end of which is closed to form a compression chamber, a tubular piston rod operating through the lower end of the cylinder, a piston fixed on the piston rod within the cylinder, there being a port formed through the bearing for the piston rod at the lower end of the cylinder and leading from the compression chamber and adapted to coincide with a port in the tubular piston rod, an auxiliary compression chamber arranged adjacent the cylinder and adapted to communicate with the compression chamber in said cylinder.

5. An internal combustion engine, comprising a cylinder, the lower end of which is closed to form a compression chamber, a piston rod operating through the lower end of the cylinder, a piston fixed on the piston rod within the cylinder, there being a port formed through a portion of the piston rod, there being a port formed through the bearing for the piston rod at the lower end of the cylinder and leading from the compression chamber, with which port the port in the piston

105

110

115

120

125

130

rod is adapted to register, there being a gas inlet port into the compression chamber, there being an exhaust port leading from the interior of the cylinder, and a deflector plate carried by the piston for partially closing the exhaust port when the piston is at the lower end of its stroke.

In testimony whereof, I have signed my name to this specification, in presence of two subscribing witnesses.

OLIVER H. SHROYER.
